UNITED STATES PATENT OFFICE.

BENJAMIN S. T. BISHOP, OF SHREWSBURY, AND HENRY A. JACOBSON, OF WORCESTER, MASSACHUSETTS, ASSIGNEES TO LELAND-GIFFORD COMPANY, A CORPORATION OF MASSACHUSETTS.

ELECTRIC REVERSING DEVICE FOR TAPPING MACHINES.

Application filed February 3, 1926. Serial No. 85,693.

This invention is particularly designed for use on combined drilling and tapping machines driven by an electric motor and relates to the reversing of the spindle so that it will turn into the work, reverse automatically, turn out again and then repeat the operation without attention of the operator.

The principal objects of the invention in addition to this are to provide a handle or lever for reversing purposes with means connected therewith adapted to be operated automatically so that the machine can be reversed in the regular way automatically or by hand at the will of the operator; to provide improved means for mounting the operating member for controlling the automatic reverse and to provide improvements in the switch.

Reference is to be had to the accompanying drawings in which

Fig. 1 is a side view of a part of a drilling machine with a preferred embodiment of this invention applied thereto;

Fig. 2 is a plan of the attachment with the motor shown in dotted lines;

Fig. 3 is a sectional view on the line 3—3 of Fig. 1;

Fig. 4 is a central sectional view of the switch proper with parts shown in elevation;

Figs. 5 and 6 are sectional views on the lines 5—5 and 6—6 respectively of Fig. 4; and

Fig. 7 is a diagrammatic view of the electrical connections.

We have shown the invention as applied to a drill used for tapping and comprising a frame 10 with a motor 11 at the top mounted on a vertical axis. The machine comprises a spindle 12 which rotates in the quill 13. The quill moves up and down with the spindle either by the usual hand or power feed and the tool is screwed into the work in case of tapping. On the quill at the rear there is a projection constituting an arm having a pivot stud 14 on which is mounted a link 15 with a spring pin 16 for engaging in a notch 17 in the arm on the quill. This lever is provided in a circular hub that surrounds the stud so that the connection can easily be detached in case the machine is operated by hand, when not tapping. On the quill arm are a pair of

projections 18 for clamping the arm on the quill.

At the end the link 15 is provided with a U-shaped yoke 20 having a notch 21 at one side for receiving a rod 22. This notch is open at the end to receive this rod. It will be understood that the arm 15 moves up and down with the quill but does not rotate with the spindle.

The rod 22 is provided with two adjustable stops or dogs 23 and with the rise or fall of the spindle these dogs at either end will move to raise or lower this rod. The rod 22 is connected to an operating lever 24 having a handle 25 for reversing the switch manually at any time during the operation. The lever 24 is connected with a rod 26 which in turn is connected to an arm 27 fixed on an operating plate 28 and oscillatable about the axis of a shaft 29. This shaft is mounted in a switch box 30 and extends through it centrally. It will be obvious that the operating plate 28 is oscillated back and forth at the ends of the stroke of the spindle. It has a projection 31 for a purpose to be described.

On the shaft 29 is keyed the plate 32 which is provided with a pair of notches 34 on opposite sides of the center which have walls or abutments at their ends constituting stops. Also this plate is provided with two opposite projections or teeth 36 which are engaged by a pair of latches 37 pivoted on the casing 30 at opposite points but both extending in the same general direction from the pivots. Spring pressed plungers 38 bear on the latches and force them yielding inward. Each latch also has a pin 39 projecting at right angles from the surface. These latches are intended to engage the teeth 36.

Loosely mounted on the shaft 29 are two plates 40 and 47. The plate 40 is provided with a convex projection 46 which is located to engage one of the pins 39 as this plate turns to release that latch. It is also provided with a pin 42 located in one of the notches 34 for the purpose of turning the plate 32 as will be seen. The plate also has another pin 43 to which is attached a spring 44 which is connected with a pin 45 on the plate 47. This plate 47 has a convex projection 41 similar to the projection 46 on the plate 40 and has the same function relative

to the other latch. This plate also has pin 48 like the pin 42 and acting in the opposite notch 34.

It will be seen also that both plates have 5 end projections extending substantially to the circumference of the casing 30 between which is located the projection 31 on the plate 28. The oscillation of the arm 27 takes with it the projection 31 which swings first 10 the plate 40 and then the other plate 47 as this projection engages their extreme ends. In Fig. 6 it has just engaged plate 40 and swung it downwardly to the position shown in which the plate 40 is locked by the pin 15 42. When the projection 31 starts back upwardly, it swings the plate 47 stretching the spring 44 until its projection 41 engages the proper pin 39 and releases the latch. Now 20 the plate 40 is released and the spring 44 swings plates 40 and 32 in the same direction until latch 37 engages notch 36. If spring 44 fails to move the plate 32 far enough to engage latch 37 in notch 36, then 25 the projection 31 moves the plate 47 further until the pin 48 engages the end of the notch 34, latching 37 in notch 36.

When the arm 27 is swung back again it 30 will have to move a little ways before engaging the free plate 40 and then it will swing that and its convex projection 46 will engage the lower pin 39 releasing this latch from the tooth 36 by which the plate 32 was 35 locked in its extreme position. The continued movement of the arm 27 swings the plate 32 back until locked by the latch 37 at the top. Thus one complete oscillation is produced.

The shaft 29 is of course oscillated in 40 bearings on the casing 30 as has been seen. The central portion of this shaft is square and provided with an insulating block 50 which necessarily oscillates with it. This is formed of insulating material and has a metal support 61 carrying two contacts 51 at each 45 end. Similar contacts 52 are carried by an opposite support 60. The contacts 52 are connected across by two wires 53 which cross each other as shown in Fig. 4. These contacts are of usual form having springs for 50 yieldingly holding them in position. An insulating piece 55 projects from the block 50 and keeps away the wires 53 where they cross and also electrically divides the metallic support 60. The two contacts 51 at one 55 side of the block 50 are connected to the other contacts 52 by the support 61 carried by the block.

Terminals 56 are shown as located opposite each other and mounted on yielding supports carried by posts 58 and connected with the line in the usual manner.

The shaft oscillates from one extreme position to the other and two contacts 52 alternately come into contact with the terminals 56. In that way contact is established as

shown in Fig. 5, from the terminal on one side, through the wire 53 to the conductor 54 on the other side and to the other contacts 51 so the current is completed in one direction. Now when the parts oscillate to 70 the opposite position, contact 52 at the bottom engages the terminal 56. The current goes through the conductor 54, and is conducted at the left side directly to the other one of the contacts 51. It will be seen that 75 in one case the current crosses over and in the other case it is directed straight through so that in one case it is delivered to the machine in one direction and in the other case in the other direction. 80

This constitutes a simple way of reversing the current in the machine and provides a device which can be operated by hand as well as automatically.

Although we have illustrated and 85 described only a single form of the invention, we are aware of the fact that modifications can be made therein by any person skilled in the art without departing from the scope of the invention as expressed in the claims. 90

Therefore we do not wish to be limited to all the details of construction herein shown and described, but what we do claim is:

1. The combination of a rod, a lever connected with said rod, a reversing switch comprising an oscillatable plate connected to be operated by said rod, a shaft on which the plate is movable, means for alternately connecting said plate with the shaft and disconnecting it therefrom, and means for conducting a current through the switch alternately in opposite directions as the plate is oscillated.

2. The combination in a reversing switch, 105 of a casing, a shaft therein, a plate oscillable on said shaft and having a projection extending from it, means for oscillating said plate, two plates mounted to swing freely on the shaft and projecting to a point to be engaged by said projection as said first named plate oscillates, whereby said plates will be moved by the projection, means operated by said plates for positively turning the shaft in one direction by one plate and in the opposite direction by the other plate, 110 and means in the casing for connecting a source of power in opposite directions according to the position of the plate.

3. In a reversing switch, the combination with a casing and a shaft therein having means for reversing an electric current, of a plate oscillable on said shaft by external means and having a projection extending from it, two plates mounted to swing freely on the shaft and projecting to a point to be engaged by said projection as said first named plate oscillates, and means operated by said plates for positively turning the shaft in one direction by one plate and in the opposite direction by the other plate. 120 125 130

4. In a reversing switch, the combination with a casing and a shaft therein having means for reversing an electric current, of a plate oscillable on said shaft by external means and having a projection extending from it, two plates mounted to swing freely on the shaft and projecting to a point to be engaged by said projection as said first named plate oscillates, whereby said plates will be moved by the projection, yielding means for swinging the plates toward each other to reduce the space between them in which the projection is located, and means operated by said plates for positively turning the shaft in one direction by one plate and in the opposite direction by the other plate.

5. In a reversing switch for the purpose described, the combination of a casing, an oscillatable shaft mounted in said casing, a plate fixed on the shaft, two plates freely oscillatable on said shaft, an oscillatable operating plate having a projection for engaging the two free plates and oscillating them, and means on the free plates for swinging the fixed plate alternately back and forth as the first named plate is oscillated.

6. In a reversing switch for the purpose described, the combination of a casing, an oscillatable shaft mounted in said casing, a plate fixed on the shaft and having a pair of elongated notches oppositely located, two plates freely oscillatable on said shaft each having a pin projecting into one of said notches, a spring connecting said free plates, and an oscillatable operating plate at the end of the casing having a projection for engaging the two free plates and operating them sufficiently to stretch the spring and swing the shaft back and forth as the operating plate is oscillated.

7. In a reversing switch for the purpose described, the combination of a casing, an oscillatable shaft mounted in said casing, a plate fixed on the shaft, two plates freely oscillatable on said shaft each having a projection for engaging the fixed plate to lock the free plate to it, an oscillatable operating plate at the end of the casing having a projection for engaging the two free plates and operating them alternately to swing the shaft back and forth as the operating plate oscillates, spring latches for engaging the fixed plate in certain positions and locking it against motion, said free plates having convex projections thereon adapted to engage said latches and disengage them from the fixed plate for unlocking the same alternately as the operating plate oscillates.

8. In a reversing switch for the purpose described, the combination of a casing, an oscillatable shaft mounted in said casing, a plate fixed on the shaft and having a pair of elongated notches oppositely located, two plates freely oscillatable on said shaft each

having a pin projecting into one of said notches to lock the free plates to the fixed plate, a spring connecting said free plates, an oscillatable operating plate at the end of the casing having a projection for engaging the two free plates alternately and operating them sufficiently to stretch the spring, and a pair of spring latches for engaging the fixed plate in certain positions and locking it alternately against motion in opposite directions, whereby when either latch is released the fixed plate and one of the free plates are released to permit the spring to turn them and the shaft, said free plates having convex projections thereon adapted to engage said latches and disengage them from the fixed plate for unlocking the same.

9. In a reversing switch, the combination of a shaft, means for oscillating said shaft, an insulating block fixed to turn with the shaft, two pairs of contacts located on opposite sides of the block, two line terminals on opposite sides of the block in position to be engaged by the contacts on the block alternately as the block and shaft swing, means for conducting the current from one contact to the other directly on one side of the block, and crossing conductors for conducting the current from one contact on the other side of the block to the opposite terminal on the first named side of the block.

10. In a reversing switch, the combination of a shaft, means for oscillating said shaft, an insulating block fixed to turn with the shaft, two sets of contacts located on opposite sides of the block, two line terminals in position to be engaged by the contacts on the block alternately as the block and shaft swing, means for conducting the current from one contact to the other directly on one side of the block, and means for conducting the current from one contact on the other side of the block to the opposite terminal on the first named side of the block.

11. A reversing switch comprising a shaft, a plate oscillatable on said shaft, means for alternately connecting said plate with the shaft and disconnecting it therefrom, and means for conducting a current through the switch alternately in opposite directions as the plate is oscillated, comprising means for oscillating said shaft, an insulating block fixed to turn with said shaft, two sets of contacts located on opposite sides of the block, two line terminals in position to be engaged by the contacts on the block alternately as the block and shaft swing, means for conducting the current from one contact to the other directly on one side of the block, and means for conducting the current from one contact on the other side of the block to the opposite terminal on the first named side of the block.

12. In a reversing switch the combination

with a casing and shaft therein, of a plate oscillatable on said shaft by external means and having a projection extending from it, two plates mounted to swing freely on the shaft and projecting to a point to be engaged by said projection as the first named plate oscillates, and means operated by said plates for positively turning the shaft in one direction by one plate and in the opposite direction by the other plate, and means for conducting a current through the switch alternately in opposite directions as the first named plate is oscillated, comprising an insulating block fixed to turn with said shaft,

two sets of contacts located on opposite sides 15 of the block, two-line terminals in position to be engaged by the contacts on the block alternately as the block and shaft swing, means for conducting the current from one contact to the other directly on one side of the block, and means for conducting the current from one contact on the other side of the block to the opposite terminal on the first named side of the block.

In testimony whereof we have hereunto 25 affixed our signatures.

BENJAMIN S. T. BISHOP.
HENRY A. JACOBSON.
